ACCOUNTING MACHINE

Alfred G. Kibler, Dayton, Ohio, assignor to The
National Cash Register Company, Dayton, Ohio,
a corporation of Maryland

Application July 31, 1943, Serial No. 496,899

10 Claims. (Cl. 271—71)

This invention relates to cash registers and accounting machines, and particularly to slip, bill, statement, or card ejecting and inverting mechanisms adapted to be used in machines of the type illustrated and described in United States Letters Patent No. 1,916,535, issued July 4, 1932, to Bernis M. Shipley, and No. 2,141,332, issued December 27, 1938, to Charles H. Arnold, and is an improvement over the ejecting mechanism shown in the patent to John Earl Gates, Re. 21,442, dated May 7, 1940. The present invention is also an improvement over an ejecting and inverting mechanism shown and described in the co-pending application for United States Letters Patent of Walter J. Kreider, Serial No. 496,122, filed July 26, 1943.

It is common practice among public utility companies such as gas and electric companies, telephone companies, and water companies to furnish their customers periodically with statements of their accounts. Such statements, before being mailed out to the customers, are usually composed of a plurality of detachable portions; namely, an office copy, a customer's statement, and a cashier's stub. Each of the different portions of the statement bears the same information identifying that particular account and the amount due for the service rendered the customer.

Such statements or bills are of varying widths and also of varying thicknesses. In some cases, the material used is of a paper substantially the same thickness as a standard governmental postal card, and again, in other instances, the statements may be on very thin or flimsy paper, which are inserted in envelopes and mailed to the customers. In the heavier type of paper, the statement itself is mailed as a postal card.

In making up the bills or statements, the operator inserts the form into the machine against a stop, after which the machine, by means of a feeding mechanism, draws the form into the machine into position to be printed upon, either once or a plurality of times, depending upon the type of bill or statement which is to be issued to the customer. Of course, if a plurality of prints are to be made, then the feeding mechanism functions between each print, so that there will be no overprint, as is fully illustrated and described in the above-mentioned Arnold and Gates patents.

After the last printing has taken place, which is usually the total of the bill or statement, the statement is fed forwardly into a position to be ejected from the machine and inverted.

It is with this ejecting and inverting mechanism that the present invention is particularly involved. In some of the machines on the market, bills or statements are fed a considerable distance, and a gripping device grasps the statement and ejects it from the machine and at the same time inverts the statements so that they will be in their proper sequential or alphabetical order, depending upon how the operator has them arranged. Sometimes, due to the very thinness of the paper used, and also even due to the fact that the paper is of a very heavy texture, the ejecting mechanism occasionally will crumple or bend the statements, and sometimes they may even catch in the machine and not be completely ejected.

To avoid such things happening, the present invention is arranged to grip the bill or statement sheet at or near the leading edge thereof, 10 after it has been printed upon and fed to the ejecting position, and eject it from the machine, and at the same time invert it so as not to destroy the sequential or alphabetical order of the stack.

15 By gripping the statement or bill near the leading edge thereof, such statement or bill is not pushed but is drawn out of the machine and at the same time automatically inverted without in any way placing any strain on the paper.

20 The present manner of ejecting and inverting the statement sheet from the machine eliminates the use entirely of a paper chute, such as has been used in many instances in the past, thus eliminating the possibility of the statement sheet sticking in the chute during the process of ejecting the same.

25 It is, therefore, an object of this invention to provide a novel combination of elements to eject and invert a statement sheet or bill from the machine after it has been printed upon, regardless of the thickness or the thinness of the material used for the bill.

30 Another object of this invention is to provide a novel ejecting and inverting mechanism for inserted statements or bills to grip the statement by the leading edge thereof after it has been fed to a designated position, and then eject said bill or statement by drawing it completely out of the machine, thus eliminating all friction which attends ejecting mechanism where the paper or statement is pushed out through a chute, thus definitely eliminating all strains and stresses on the paper and preventing crumpling or buckling thereof.

35 Another object of this invention is to provide

a novel rotatable ejecting and inverting mechanism for statement sheets, including a floating member carrying a pivoted gripping finger and a single member to drive the floating member and control the gripping finger.

With these and incidental objects in view, the invention includes certain novel features of construction and combinations of parts, the essential elements of which are set forth in appended claims and a preferred form or embodiment of which is hereinafter described with reference to the drawings which accompany and form a part of this specification.

Of said drawings:

Fig. 1 is a view showing a portion of the ejecting and inverting mechanism in its normal position and also shows the operating means for said mechanism.

Fig. 2 is a detail view of a portion of the ejecting mechanism, showing the actuating means or driver for the ejecting device and the gripping finger.

Fig. 3 is a front view, partially broken away, showing the ejecting and inverting mechanism in the normal position.

Fig. 4 is a detail view of the statement sheet deflector and the operating mechanism therefor.

Fig. 5 is a detail view of a portion of the ejecting mechanism in the moved position, after the gripping finger has been opened and the statement sheet, shown in dotted lines, fed into a position to be gripped by the gripping finger.

Fig. 6 is an enlarged detail view of a portion of the gripping finger, showing the serrations on the outside thereof, which cooperate with the statement sheet or bill.

Fig. 7 is a detail view of a portion of the ejecting mechanism, showing the gripping finger gripping the statement sheet, the parts being in the positions they assume just prior to the beginning of the ejecting movement of the parts.

Fig. 8 is a detail view showing a portion of the ejecting mechanism in the position it assumes after the statement sheet has been ejected and inverted, and just after the statement sheet is released by the gripping finger.

GENERAL DESCRIPTION

Described in general terms, the present invention in the specific embodiment shown comprises a pair of ejecting devices mounted to float on a shaft and adapted to be driven by a pair of actuators or driving arms which are secured to the shaft.

The ejecting device includes curved plates or flanges carried by substantially circular plates, which plates have pivoted thereto gripping levers with fingers adapted to cooperate specifically with the flanges, under the influence of springs.

To drive the substantially circular plates and the gripping devices, there is provided a pair of arms secured to a shaft which is driven through a rack and pinion under the power of a camming device.

This pair of driving arms also operates the gripping levers to release the gripping fingers from the gripping position so that the statement sheets or bills can be properly stacked after they have been ejected and inverted by applicant's novel mechanism.

The invention herein is shown as having been applied to a machine of the type shown in the above-mentioned Arnold Patent No. 2,141,332.

Therefore only a small portion of the mecha-

nism of that patent is shown herein in Fig. 1. This mechanism includes a part of the statement sheet feeding mechanism, a type wheel, one of the hammers, and a driving or operating mechanism for the ejecting and inverting mechanism.

DETAILED DESCRIPTION

As has been previously stated, a small portion of the printing and feeding mechanism of the type shown and described in the above-mentioned Arnold Patent No. 2,141,332 has been shown herein, in order to show the relationship between such printing and feeding mechanisms and the novel ejecting and inverting mechanism of the present application.

The greater part of the printing mechanism is supported between side frames 61 and 62 (Figs. 1 and 3), which are secured to a base (not shown) and which are connected by several tie bars 63 (only one being shown).

Statement sheet or slip feed rollers 64 (only one being shown) are secured to a shaft which is supported by the frames 61 and 62. The feed rollers 64 are driven through the rotation of a shaft 65 by means fully illustrated and described in the above-mentioned Arnold and Gates patents. The feeding rollers 64 are notched to provide stopping shoulders 66 to form locating positions for a statement sheet or slip 70 when it is first inserted into the machine by the operator.

Pressure rollers 71 (only one being shown) cooperate with the feed rollers 64 to feed the statement sheet 70 into the machine, into position to be printed upon, and also line-space it when necessary to do so, according to the number of prints to be made thereon. The printing is accomplished by type wheels 72 and pivoted hammers 73.

A table 74 is supported on top of the frames 61 and 62, upon which table the statement sheet 70 is placed prior to its initial insertion into the machine against the shoulder 66, which position is shown in Fig. 7.

A pivoted deflector 75 is used to guide the statement sheet 70 when it is being inserted into the machine. This deflector 75 is shown in its normal position in Fig. 1. In Figs. 4 and 5, it is shown in the position it assumes prior to the printing, which position it retains until after the statement sheet 70 has been fed outwardly by the rollers 64.

With the deflector 75 in the normal position, shown in Fig. 1, the operator inserts a statement sheet 70 underneath the deflector 75 and up against the shoulders 66 into the position shown in full lines in Fig. 7. After this insertion, the feed rollers 64 are rotated clockwise to feed the statement sheet 70 into the machine, into position to be printed upon by the type 72. This position is shown by the dot-and-dash lines in Fig. 7. Other step-by-step feeds may or may not take place, depending upon whether or not there is to be one or a multiplicity of prints made upon the statement sheet 70. After the printing has taken place, the rollers 64 feed the statement sheet forwardly or toward the front of the machine (Figs. 5 and 7). Prior to the printing and this latter feeding of the statement sheet 70 toward the left, as just described, the deflector 75 is moved from the position shown in Fig. 1 to that shown in Figs. 4 and 5, in order to deflect the statement sheet 70 downwardly so that it will not come out on top of the table 74 but will be moved into a position as shown in Fig. 5, where it is then ready to be ejected from the

machine by the ejecting mechanism and at the same time automatically inverted so as to maintain the proper sequential numerical or alphabetical order of the sheets as they are stacked.

The deflector 75 is secured to a shaft 76, which has fastened thereto an arm 71 carrying a pin 78 engaged by a forked arm 79 pivoted on a shaft 80. The shaft 80 is carried by the side frames 61 and 62 and is supported intermediate its ends by brackets 81, which are fastened to the tie bar 63. The arm 79 has a finger 82 (Figs. 1 and 4), which is held in contact with a stud 83 by a spring 84 stretched between a stud on the arm 79 and the stud 83, which is carried by a lever 85.

This lever 85 is also pivotally mounted upon the shaft 80 and has a finger 86 normally held in contact with a stud 87 on the frame 62 by a spring 88 (Fig. 1). Secured to the shaft 80 is an operating arm 90, shown in the normal position in Fig. 1.

The shaft 80 is adapted, by means to be herein-after described, to be given first a clockwise movement and then a counter-clockwise movement back to its normal position. Upon the clockwise movement of the shaft 80, the arm 90 engages a stud 91 carried by the lever 85 and rocks the lever 85 clockwise from the position shown in Fig. 1 to the position shown in Fig. 4. During this clockwise movement of the lever 85, the spring 84 causes the finger 82 to remain in contact with the pin 83 on the lever 85 and consequently rocks the arm 79 in a clockwise direction, which, through the pin 78, rocks the arm 71, the shaft 76, and the deflector 75 counter-clockwise from the position shown in Fig. 1 to that shown in Figs. 4 and 5.

The deflector is maintained in this position shown in Figs. 4 and 5 for approximately 180 degrees of time, or until after the statement sheet 70 has been moved into the position shown in Fig. 7 by the feeding rollers 64, after which the shaft 80 and the operating arm 90 are returned in a counter-clockwise direction from the position shown in Fig. 4 to the normal position, shown in Fig. 1. During this counter-clockwise movement of the arm 90, the spring 88 causes the pin 91 to follow the arm 90 until the finger 86 of the lever 85 contacts the stop stud 87, which is the normal position of the lever 85. During this counter-clockwise movement of the lever 85, the pin 83, under the influence of the spring 88, rocks the finger 82 and the arm 79 counter-clockwise from the position shown in Fig. 4 to the position shown in Fig. 1, thus moving the deflector 75 back to its normal position in Fig. 1.

The means for operating the shaft 80 first clockwise and then counter-clockwise, as above described, includes a pinion 92 secured to the end of the shaft 80, as shown in Figs. 1 and 3. Meshing with this pinion is a rack 93. The rack 93 has a smaller rack 94 secured to the side thereof, which meshes with a gear 95 having fastened thereto a pinion 96, which in turn meshes with a gear segment 97. The gear segment 97 carries a roller 98 cooperating with a cam 99 fast on a cam shaft 100. This cam shaft 100, as is fully illustrated and described in the above-mentioned Arnold and Gates patents, receives one clockwise rotation for each operation of the machine. During this operation, the cam 99, through the roller 98, rocks the segment 97 clockwise and, through the rack 94, the gears 95 and 96, and the rack 93, rotates the pinion 92 in a

clockwise direction, thus turning the shaft 80 likewise.

The cam 99 is so timed that the shaft 80 is held in its clockwise moved position for substantially 180 degrees of time, after which there is a sharp drop-off on the cam 99, whereupon a spring 101 connected to the rack 93 returns the rack 93 to the right very rapidly, thus rapidly rotating the pinion 92 and the shaft 80 counter-clockwise, so that the ejecting and inverting mechanism to be herein-after described will be operated to quickly eject and invert the statement sheet.

Ejecting and inverting mechanism

In the preferred form of embodiment shown, the novel ejecting and inverting mechanism includes a pair of substantially circular plates 110 freely mounted on the shaft 80. Each plate 110 has a right-angled lip 111, to which is secured an arcuate-shaped finger 112, with which cooperates a gripping finger 113 of a lever 114 pivoted on a pin 115 carried by the plate 110. In the normal positions of the parts as shown in Fig. 2, a spring 116, connected to a stud 117 on the lever 114 and a stud 118 on the plate 110, holds the gripping finger 113 in contact with the inner side of the finger 112. The finger 113 has serrations 119, shown only in the enlarged drawing (Fig. 6), to insure a good grip on the sheet 70. The lever 114 also carries a pin 120 for cooperating with a driving arm 121 in a manner to be herein-after described. This arm 121 also cooperates with a pin 122 carried by the plate 110.

The lever 114 carries a roller 125 projecting through an opening 126 in the plate 110 to cooperate with a cam 127, which is angularly adjustable around the shaft 80. For this purpose of adjustment, the cam 127 is provided with a pair of studs 128 (Figs. 3 and 5), which project through concentric slots 129 in the stationary bracket 81. By means of the slots 129 and the studs 128, the cam 127 can be angularly adjusted around the shaft 80 to bring its control surface 130 in the desired position to cooperate with the roller 125 of the lever 114. After the control surface 130 has been adjusted to the proper position, the cam 127 is locked in its adjusted position by means of nuts 131.

OPERATION

The operation of the novel ejecting and inverting mechanism above described is as follows:

In Fig. 1, the parts are all shown in their normal positions, and the statement sheet 70 is shown as having been inserted in the machine against the shoulder 66 of the feeding roller 64, ready to be drawn into the machine by the feeding mechanism into the first printing position.

As has been previously stated, the statement sheet 70 is fed into the machine to the printing line and printed upon by the type wheel 72 through the action of the hammers 73. There may be one print made on the statement sheet or there may be several prints made thereon, depending upon the system and the information desired to have placed on the statement sheets before they are mailed out. However, after the final printing, which, as above stated, is usually the total, the statement sheet is fed into the position shown in Fig. 7.

Prior to the printing and this feeding of the statement sheet into the position shown in Fig. 7, the rack 93 (Fig. 1) is moved to the left, as

viewed in Fig. 1, thus rotating the shaft 80 in a clockwise direction. During this clockwise movement of the shaft 80, the operating arms 121 are of course moved clockwise and the floating or loosely mounted plates 110 move clockwise, keeping the pins 122 against the arms 121, due to the fact that most of the weight of the plates 110 is, in the normal position, on the right-hand side of the shaft 80, as viewed in Fig. 2. However, as the arms 121 continue their clockwise movement, the gap between said arms and the pins 120 on the gripping levers 114 will be closed, and the arms 121 continue to carry the plates 110 in a clockwise direction until the parts reach the positions shown in Fig. 5.

When the plates 110 have reached the position shown in Fig. 5, a stud 134 on each plate 110 contacts a square stud 135 on each stationary bracket 81, thus stopping the clockwise movement of the plates 110. After this, the shaft 80 and the arms 121 have still a slight clockwise movement to go to reach the maximum position of their clockwise rotation, during which time the arms 121, through their engagement with the pins 120, rock the levers 114 counter-clockwise around their pivot studs 115, thus opening the gripping fingers 113, or, in other words, moving these fingers 113 away from the inside of the fingers 112, so that the statement sheet 70 may be fed between the fingers 112 and the fingers 113, as is shown in Fig. 5. In this figure, the statement sheet 70 is shown as just entering the space between the fingers 112 and 113, and in Fig. 7 the statement sheet is shown as having been fully fed by the feeding rollers 64 just prior to the time the ejecting and inverting take place.

After all of the printing has taken place on the statement sheet and the sheet is in the position shown in Fig. 7, the cam 99 releases the segment 97 to the action of the spring 101, whereupon the rack 93 is rapidly moved to the right into the position shown in Fig. 1, thus rotating the shaft 80 and the arms 121 in a counter-clockwise direction to their normal position. During the very first part of this counter-clockwise movement of the arms 121, they move away from the pins 120 and contact the pins 122 on the plates 110. As the arms 121 leave the pins 120 on the levers 114, the springs 116 rock the levers 114 from the position shown in Fig. 5 to the position shown in Fig. 7, thus causing the fingers 113 to firmly grip the statement sheet between themselves and the inner sides of the fingers 112.

Now, the further counter-clockwise rotation of the arms 121, by their engagement with the pins 122 on the plates 110, rocks the plates 110 counter-clockwise, whereupon the fingers 112 and 113 eject the statement sheet 70 from the machine. These fingers carry the statement sheet from the position shown in Fig. 7 into the position shown in Fig. 8. When the statement sheet reaches the position shown in Fig. 8, it has been ejected and inverted from the printing mechanism, and its leading edge comes into contact with edges 136 of the stationary brackets 81. Just prior to the contact of the leading edge of the statement sheet 70 with the edges 136 of the brackets 81, the rollers 125 of the levers 114 have contacted the high surfaces 130 of the cams 127, thus rocking the levers 114 counter-clockwise against the action of the springs 116, thereby opening up the fingers 113 and 112, or, in other words, removing the fingers 113 away from the statement sheet 70, thus leaving the statement sheet free, as shown in Fig. 8.

Now, upon the further counter-clockwise movement of the plates 110 to their normal position (that is, from the position shown in Fig. 8 back to the position shown in Fig. 2), since the leading edge of the statement sheet 70 is contacting the edges 136 of the brackets 81, the statement sheet 70 cannot move any farther, and consequently the open fingers 113 and 112 will be moved past the edges of the statement sheet 70, whereupon it will fall into a receptacle 137 (Fig. 1) with its printed side down, or, in other words, inverted from the position in which it was inserted into the machine.

It might be stated here that, at the time the plates 110 are being rocked in a clockwise direction from the position shown in Fig. 2 to the position shown in Fig. 5, the rollers 125 of the levers 114 contact the high surfaces 130 of the stationary cams 127 and open the fingers 112 and 113, but during this time, since there is no paper or statement sheet in between the fingers, this movement is merely an idle one, and, as soon as the rollers 125 pass off the upper side of the high surfaces 130, the springs 116 rock the levers 114 into a position whereby the fingers 113 again contact the inside of the fingers 112.

While the form of mechanism herein shown and described is admirably adapted to fulfill the objects primarily stated, it is to be understood that it is not intended to confine the invention to the form or embodiment herein disclosed, for it is susceptible of embodiment in various forms all coming within the scope of the claims which follow.

35. What is claimed is:

1. In a device for ejecting and inverting record material, the combination of oscillating means; floating means; pivoted means carried by said floating means; means on said pivoted means and cooperating with the oscillating means whereby the floating means is moved in one direction along with the oscillating means; and means carried by the floating means and cooperating with the oscillating means to cause the floating means to be moved in the reverse direction by the reverse movement of the oscillating means.

2. In a device for ejecting and inverting record material, the combination of oscillating means; floating means; pivoted means carried by said floating means; means on said pivoted means to cooperate with said floating means to grip the record material; means on the pivoted means and on the floating means cooperating with the oscillating means whereby the oscillating means oscillates the floating means; camming means; and means carried by said pivoted means to cooperate with said camming means to rock said pivoted means to release the record material.

3. In a device for ejecting and inverting record material, the combination of oscillating means; floating means; pivoted means carried by said floating means; means on said pivoted means to cooperate with said floating means to grip the record material; means on the pivoted means and cooperating with the oscillating means when the oscillating means is moved in one direction to cause the oscillating means to drive the floating means and move said pivoted means into a position so that the record material may be inserted between the means on the pivoted means and the floating means; means on the floating means and cooperating with the oscillating means to cause the oscillating means to rock the floating means in the reverse direction to its home position; means to rock the pivoted means in the

opposite direction upon said reverse movement of the floating means to cause the means on the pivoted means to grip the record material between itself and said floating means; and means to again rock said pivoted means during the time the floating means is moved in said reverse direction to release the record material from the floating means and the means carried by the pivoted means.

4. In a device for ejecting and inverting record material, the combination of oscillating means; floating means; pivoted means carried by said floating means and adapted to cooperate with said floating means to grip the record material therebetween, eject and invert it from the machine; means on the pivoted means and cooperating with the oscillating means to cause the oscillating means to rotate the floating means into a position to bring the pivoted means into position to have the record strip pass between itself and the floating means; and means on the floating means and cooperating with said oscillating means to cause the oscillating means to reversely rotate the floating means to cause the pivoted means and the floating means to eject and invert the record material.

5. In a device for ejecting and inverting record material, the combination of oscillating means; floating means; pivoted means carried by said floating means and adapted to cooperate with said floating means to grip the record material therebetween, eject and invert it from the machine; means on the pivoted means and cooperating with the oscillating means to cause the oscillating means to rotate the floating means into a position to bring the pivoted means into position to have the record strip pass between itself and the floating means; means on the floating means and cooperating with said oscillating means to cause the oscillating means to reversely rotate the floating means to cause the pivoted means and the floating means to eject and invert the record material; and a camming device cooperating with said pivoted means to move the same to release the record material after it has been ejected and inverted.

6. In a device for ejecting and inverting record materials, the combination of oscillating means; floating means; pivoted means carried by said floating means and adapted to cooperate with said floating means to grip the record material therebetween, eject and invert it from the machine; means on the pivoted means and cooperating with the oscillating means to cause the oscillating means to rotate the floating means into a position to bring the pivoted means into position to have the record strip pass between itself and the floating means; means on the floating means and cooperating with said oscillating means to cause the oscillating means to reversely rotate the floating means to cause the pivoted means and the floating means to eject and invert the record material; and a stationary camming device cooperating with said pivoted means during the return movement of the floating means to its normal position to move the pivoted means to release the record material after the same has been ejected and inverted from the machine.

7. In a device for ejecting and inverting record material, the combination of oscillating means; floating means; pivoted means carried by the floating means and adapted to cooperate with the floating means to grip, eject and invert the record material from the machine; and a plurality of projections, one on said floating means and one on said pivoted means, both projections cooperating with said oscillating means to cause the oscillating means to oscillate the floating means to bring the pivoted means into position to grip, eject and invert the record material from the machine.
8. In a device for ejecting and inverting record material, the combination of oscillating means; floating means; pivoted means carried by said floating means for cooperating with the floating means to grip the record material, eject it from the machine and at the same time invert it; projecting means on said floating means; projecting means on said pivoted means; and means carried by said oscillating means and extending between said projecting means to move the floating means and the pivoted means into position to grip the record material, and to move the floating means and the pivoted means to eject the record material from the machine and invert it.
9. In a device for ejecting and inverting record material, the combination of an oscillating shaft; floating means; pivoted means carried by said floating means for cooperating with the floating means to grip the record material, eject it from the machine, and at the same time invert it; projecting means on said floating means; projecting means on said pivoted means; means carried by said oscillating shaft and extending between said projecting means to move the floating means and the pivoted means into position to grip the record material, and to move the floating means and the pivoted means to eject the record material from the machine and invert it; and means cooperating with said pivoted means to rock the same to release the record material from the pivoted means and the floating means after said record material has been ejected and inverted.
10. In a device for ejecting and inverting record material, the combination of an oscillating shaft; floating means; pivoted means carried by said floating means for cooperating with the floating means to grip the record material, eject it from the machine, and at the same time invert it; projecting means on said floating means; projecting means on said pivoted means; means carried by said oscillating shaft and extending between said projecting means to move the floating means and the pivoted means into position to grip the record material, and to move the floating means and the pivoted means to eject the record material from the machine and invert it; and means for moving said pivoted means after said record material has been ejected and inverted to release said record material from the ejecting and inverting floating means and pivoted member.

ALFRED G. KIBLER.
